UNITED STATES PATENT OFFICE.

CLARENCE C. WILSON, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

NON-HEAT-CONDUCTING RECEPTACLE.

1,076,804.

Specification of Letters Patent.

Patented Oct. 28, 1913.

Application filed August 28, 1912. Serial No. 717,435.

To all whom it may concern:

Be it known that I, CLARENCE C. WILSON, a citizen of the United States of America, and a resident of the city of Bridgeport, 5 county of Fairfield, and State of Connecticut, have invented a new and useful Improvement in Non-Heat-Conducting Receptacles, of which the following is a specification.

10 My invention relates to non-heat-conducting receptacles in which air spaces or chambers are provided at the top, bottom and sides of the receptacle.

The receptacles may be made of any suitable material, although I prefer to make them of a suitable substantially non-heat-conducting material such as paper box board.

15 The receptacles may be placed on the market either wholly or partially in knock-down form or may be made-up ready for immediate use. For convenience in packing and shipping the knock-down form is preferable.

20 25 The object of the invention is to provide a non-heat-conducting receptacle suitable for use in connection with the transportation or preservation of food stuffs, either solid or liquid and whether hot or cold, the inner portion or container of the receptacle being substantially insulated against either the diffusion or absorption of heat.

30 35 A further object of the invention is to provide a receptacle of the class described which will be cheap and easy to make as well as efficient in use.

In the following I have described, in connection with the accompanying drawings, several forms of structure illustrating the 40 application of the principles of my invention, the novel features thereof being more particularly pointed out hereinafter in the claims.

45 In the drawings Figure 1 is a longitudinal sectional view of one form of receptacle illustrating my invention as applied to a cylindrical inner container of the kind particularly useful in connection with the transportation or preservation of liquid or semi-50 liquid food stuffs; Fig. 2 is a vertical cross-sectional view of the structure shown in Fig. 1, along the line 2—2, looking in the direction of the arrows; Fig. 3 is a plan view of one of the side spacers; Fig. 4 is a plan view of 55 one form of an end spacer in the flat;

Fig. 5 is an elevation of the structure shown in Fig. 4 made up into a cone shape; Fig. 6 is a perspective view of one end of the outer container showing the locking means; Fig. 7 is a longitudinal sectional view of another form of receptacle illustrating my invention as applied to an inner container rectangular in cross-section; Fig. 8 is a vertical cross-sectional view of the structure shown in Fig. 7, along the line 8—8, looking in the direction of the arrows; Fig. 9 is a plan view of a form of side spacer adapted for use in connection with an inner container rectangular in cross-section; Fig. 10 is a perspective view of a form of end spacer adapted for use in connection with any form of inner container; Fig. 11 is an elevation of a portion of the end spacer shown in Fig. 10; Fig. 12 is a plan view of a form of end spacer, in the flat, especially adapted for use in connection with inner containers rectangular in cross-section and Fig. 13 is an elevation of the structure shown in Fig. 12 made up into pyramidal shape.

Similar letters of reference indicate similar parts throughout the several views.

a indicates an inner container cylindrical in shape and made of any suitable material such as glass, wood, paper box board, or the like. As this form of receptacle is especially adaptable for use in connection with liquid or semi-liquid food stuffs, if it is made of a material normally permeable to liquids, I prefer to treat the same so as to render it impervious to liquid.

b indicates an outer container, preferably rectangular in cross-section, made of any suitable material such as paper box board, strawboard, metal, glass, basket-weaving, etc. For its largest use both the inner and outer containers, as well as the other parts of the receptacle, may be made of paper box board and, where the construction or form permits, in knock-down form. The ends of the outer container b may be interlocked as shown in Fig. 6, where c, c' indicate the inner interlocking flaps and d, d' indicate the outer interlocking flaps. In this form of construction of the ends of the outer container, no reasonable pressure from within the receptacle can spring or force open the ends when once interlocked.

The ends of the inner container a are preferably recessed as shown in Fig. 1, where e indicates the recessed bottom and f

indicates a recessed cover fitting over the edges of the container.

5 *g* indicates a side spacer of any suitable material, as hereinabove set forth, the outer periphery of which is cut to fit closely the inner face of the outer container. The central portion of spacer *g* is cut out to form an aperture *h* adapted to fit closely the outer wall of the inner container *a*. The spacers 10 *g*, one, two or more in number, as may be desirable, are slipped over the inner container and are held substantially at right angles thereto, preferably by friction. The end spacers *i* for a cylindrical inner container 15 are preferably cone shaped so as to provide but a single point of contact where the same touches the inner walls of the ends of the outer container. The end spacers may be made of a circular piece *j* of suitable material 20 having a radial slit *k* so that one portion may be slid under the other to form a cone as shown in Fig. 5. When the end spacers *i* are placed in the recesses at the ends of the inner container, slight pressure at the point 25 of the cone will cause them to spread and frictionally engage the walls of the recesses. When the side spacers *g* and end spacers *i* are in position, the inner container *a* may be slid into the outer container *b*, the side 30 spacers frictionally engaging the inner face of the outer container and the points of the cones of end spacers *i* contacting with the inner walls of the ends of the outer container as shown in Fig. 1. By the means described 35 it is obvious that an air space or chamber is formed between the inner and outer containers with minimal points of contact between them.

The structure shown in Fig. 7 differs 40 from that shown in Fig. 1 in that the inner container *a'* is rectangular instead of cylindrical. The outer container *b* is the same in both cases. In the structure shown in Fig. 7, the end spacers *l* are preferably pyramidal in shape, the base of the pyramid resting against the inner ends of the outer container and the apex against the end of the inner container, thus forming but a single point of contact. This form of end spacer 45 50 may be cut in the form shown in Fig. 12 and of a size to fit the ends of the outer container. It is then folded or bent into pyramidal form as shown in Fig. 13.

End spacers such as shown in Figs. 10 55 and 11 may be used in place of end spacers of the form shown in Figs. 4 and 5 and Figs. 12 and 13. The end spacers shown in Figs. 10 and 11 comprise two strips of material *m*, *m'* of any suitable kind, mortised together as shown. Such end spacers may be substituted for the other forms at either or both ends of the receptacle.

The end spacers of the forms shown in Figs. 1 and 7, are characterized as to shape 60 in being tapering, while those of the con-

struction shown in Figs. 10 and 11 are flat; but in all cases these spacers leave large air spaces between the end walls of the outer container and the adjacent ends of the inner container. The end spacers and intermediate spacers *g* support the inner container free of direct contact with the outer container and with air spaces wholly surrounding the inner container.

All of the various forms of end spacers 75 herein explained are of hollow form, as distinguished from solid, so as to present linear contact only with at least one of the containers and avoid extended surface contact therewith, and they also serve to form 80 air chambers between the inner and outer containers, so that in conjunction with the intermediate spacers the inner container is in effect suspended in air within the outer container.

In an actual test of a receptacle of the type shown in Fig. 1, water having a temperature of 50° F. suffered no appreciable gain in temperature after a lapse of two 85 hours.

It is obvious that the material, the shape and dimensions of the parts, the form of the end and side spacers and the shape and construction of the containers are immaterial and I do not restrict myself to the details as shown and described further than the scope of the appended claims demand.

What I claim and desire to secure by Letters Patent is:

1. A non-heat-conducting receptacle, comprising an outer container, an inner container, a spacer frictionally engaging the inner container intermediate the ends thereof and resting against the inner walls of the outer container, and end spacers of hollow form arranged between the ends of the inner and outer containers and engaging restricted areas of both less than the opposed areas of such containers and forming air chambers between the containers, said inner container being in effect suspended by the spacers within the outer container.

2. In a non-heat-conducting receptacle including an outer and an inner container, a spacer between the ends of the containers shaped to provide a linear contact with the end of one container and a point contact with the end of the other container.

3. A non-heat-conducting receptacle, comprising an outer container, an inner container having recessed ends, expandible spacers of taper form sprung into place in the recessed ends of the inner container and adapted to contact with the end walls of the outer container, and transversely arranged spacers for supporting the inner container between the longitudinal walls of the outer container.

4. A non-heat-conducting receptacle, comprising an outer container, an inner con-

5 tainer, transversely arranged spacers engaging the longitudinal walls of the outer container and supporting the inner container within the outer container and out of contact with its walls and with an intermediate surrounding air space, and tapering end spacers in extended superficial contact, with the inner container and having only point contact with the end walls of the outer

10 container.

5. A non-heat-conducting receptacle comprising an outer rectangular container of paper box board, a cylindrical inner container of paper box board substantially impervious to moisture, a spacer of paper box board frictionally engaging the inner container and the inner wall of the outer container and cone shaped end spacers of paper box board between the ends of the inner and outer containers, the point of the cone being

adapted to contact with the inner wall of the ends of the outer container.

6. A non-heat-conducting receptacle comprising an outer container, an inner container, a spacer frictionally engaging the ends thereof and resting against the inner walls of the outer container and pointed end spacers between the ends of the inner and outer containers, the point of the end spacer being adapted to contact with the end of one of the containers.

In testimony whereof I have signed this specification in the presence of two subscribing witnesses.

CLARENCE C. WILSON.
